DESIGN FOR A COMBINED BOOKCASE AND CABINET FOR RADIOPHONE

Jan Streng, New York, N. Y., assignor to Colonial
Radio Corporation, Buffalo, N. Y., a corpora-
tion of New York

Application November 2, 1933. Serial No. 49,633
Term of patent 3½ years

To all whom it may concern:

Be it known that I, JAN STRENG, a citizen of the United States, residing at 66 Fifth Avenue, New York, in the county of New York and State of New York, have invented a new, original and ornamental Design for a Combined Bookcase and Cabinet for Radioplane, of which the following is a specification, reference being had to the accompanying drawing, forming part thereof, in which

Fig. 1 is a perspective view of the combined

bookcase and radioplane showing the doors swung into outward position to cover the bookcase, and

Fig. 2 is a similar view showing the doors swung into inward position to cover the radioplane.

I claim:

The ornamental design for a combined bookcase and cabinet for radioplane substantially as shown.

JAN STRENG.
